(57) **CLAIM**

The ornamental design for a deck installation track, as shown and described.

DESCRIPTION

FIG. 1 is a perspective view of deck installation track; FIG. 2 is a top view of the deck installation track; FIG. 3 is a bottom view of the deck installation track; FIG. 4 is a front view of the deck installation track; and, FIG. 5 is a side view of the deck installation track. The figures illustrate a deck installation track. The broken lines in the drawings illustrate portions of a deck installation track which form no part of the claimed design. The deck installation track is shown with a symbolic break in its length. The appearance of any portion of the article between the break lines forms no part of the claimed design.
